UNITED STATES PATENT OFFICE.

JAMES G. CURRIE, OF PHILADELPHIA, PENNSYLVANIA, ASSIGNOR TO SIBSON & STERN, INC., OF PHILADELPHIA, PENNSYLVANIA, A CORPORATION OF PENNSYLVANIA.

ORNAMENTAL FABRIC EDGING.

Application filed December 24, 1920. Serial No. 433,060.

To all whom it may concern:

Be it known that I, JAMES G. CURRIE, a citizen of the United States, residing in the city and county of Philadelphia and 5 State of Pennsylvania, have invented certain new and useful Improvements in Ornamental Fabric Edgings, whereof the following is a specification, reference being had to the accompanying drawings.

10 My invention relates to fabric structures useful as ornamental edgings for women's underwear and the like, and more especially to edgings of the type adapted to be folded longitudinally, and the overlapped borders 15 united, in the course of attachment about the neck band or arm holes of the underwear to serve as tubular retainers for the concealment of draw strings or ribbons ordinarily essential to such garments.

20 The object of my invention is to characterize such a fabric by vesting it with a tendency to fold readily along a longitudinally running line of demarcation. Edging having this property not only lends itself readily to folding with positive evenness but is 25 moreover capable of withstanding the handling necessary in the course of its being attached to the garments without in any way yielding to distortion of the fold.

30 Other advantages of my invention will also become apparent from the detailed description which follows:

In the drawings, Fig. I is a diagrammatic illustration of an edging conveniently 35 embodying my invention, and showing it as a flat web, in which condition it is formed by the producing machine.

Fig. II is a diagrammatic cross sectional view of the structure upon an enlarged 40 scale.

Fig. III shows the appearance of the edging after having been folded.

Fig. IV is a cross sectional view corresponding to the showing of Fig. III.

45 Fig. V is an illustration suggestive of the manner in which the edging is applied to an undergarment; and

Fig. VI is a detail cross section at one of the regions of attachment of the edging to 50 the undergarment, the plane of the section being indicated by the arrows VI—VI in Fig. V.

55 Referring first to Fig. I, it will be observed that the fabric edging, there conventionally represented, is in the form of a narrow knit

web comprising, as an integral structure, two separate and distinct strips 1—2, which are similar in the character of their texture, and joined by a longitudinal suture 3 along the median line of the web. The strips 1—2 60 may be of any appropriate design, and for the purposes of convenient illustration, are herein shown as composed of a series of longitudinally running rows of chain loops united by transverse inlay threads after a manner common to so called lace or open work capable of being readily knit on an ordinary lace knitting machine. From the adjacent borders of the strips 1—2, extend scallop loops 5—6 respectively, which, in the course of the knitting of the web, are interlinked or intertwined as shown in the illustration. The anchorage of these loops may be incorporated with the fabric in any 70 approved manner as will be readily understandable by those skilled in the art of lace knitting.

By studying for a moment the cross section of the web as conventionally represented in Fig. II, it will be apparent that the character of the interlinking of the scallop loops 5—6 of the respective strips 1—2 is such as to afford what may be termed a hinge structure having a tendency to promote the ready folding of the fabric along the median suture in the direction suggested by the arrows in said figure, and which at the same time has the additional property of tending to resist folding in the opposite direction on account of the reluctance of the interlinked 80 scallop loops to permit of their being permanently bent about each other. The appearance of the edging when folded according to its characteristic inclination is shown in Figs. III and IV wherefrom it will be seen 85 that the scalloped loops serve, in addition to the function already pointed out, as an ornamental fringe which enhances the attractiveness of the edging.

On account of its aptness to fold in the 90 manner described above, the edging of my invention lends itself readily to spooling in the folded condition without requiring pressing beforehand, and will, without yielding to distortion, withstand the handling necessary when guided through the stitch forming elements of a sewing machine in the course of being permanently attached to the garments. One way in which the edging 95 may be applied to an undergarment is illus- 100

105

110

trated in Figs. V and VI, and may be briefly described as follows: The borders of the folded edging are placed or gauged in such a manner as to overlap a comparatively narrow margin at each side of the edges of the fabric of the under-garment (see Fig. VI) both along the neck opening 11 and arm holes 12—12, and secured by sewing as indicated conventionally at 13. Such attachment may be readily effected by employment of any suitable sewing machine of the type ordinarily used in the manufacture of underwear. The edging after being applied as above described serves to conceal the draw strings or ribbons, the ends of which, according to approved practice as illustrated for example in the case of the neck opening are brought through a suitable opening in the front of the garment, so as to be capable of being tied in a bow 14.

The particular application of the edging as described herein forms no part of the present invention, it having been shown merely for the purpose of illustrating one of the many ways of its application to practical use. The characteristic folding suture 3, if desired, may be obviously disposed in any position other than the median line of the fabric structure if the exigencies of practice should so dictate, and therefore, I do not wish to be limited to the precise showing set forth and described herein.

Having thus described my invention, I claim:

- 35 1. As a new article of manufacture an ornamental edging for female underwear consisting of a knit fabric longitudinally divided by a suture formed by correlation of fabric structural elements, thereby to promote a folding tendency in the fabric along said suture in one direction only.
- 40 2. As a new article of manufacture an ornamental edging for female underwear consisting of a knit fabric longitudinally divided by a suture of component structural elements interlaced to set up an inherent tendency in the fabric to fold along said suture in one direction only.
- 45 3. As a new article of manufacture an ornamental edging for female underwear consisting of an integral knit fabric comprising two separate and distinct strips of even width arranged side by side, and a line of interlinked marginal scallops connecting the edges of said strips to afford a suture, along the longitudinal median line of the fabric,

having the characteristic property of tending to promote folding of the fabric along said line.

4. An ornamental edging fabric for female 60 underwear having a line of loops forming a suture, said loops consisting of scalloped tissues of the fabric, and interlinking them so as to promote folding of the fabric along the suture in one direction only. 65

5. An ornamental edging fabric for female underwear having two series of loops consisting of threads of the fabric, the loops of one series being interlinked with those of the other series so as to form a suture adapted 70 to promote folding of the fabric along said suture in one direction only.

6. A fabric edging for female underwear comprising a pair of webbing strips, and a series of loops formed along one edge of each strip, the loops of one series being inter-linked with those of the other series to form a suture adapted to promote folding of the strips, one upon the other, along the suture in one direction only and to resist folding in 80 the other direction. 75

7. In a fabric edging for female underwear, two series of loops, each loop of one series enclosing the adjacent ends of an adjacent pair of loops of the other series to form 85 a suture adapted to promote folding of the fabric along said suture.

8. In a fabric edging for female underwear, a line of intertwined and opposingly fashioned component loops forming a suture adapted to promote folding of the fabric along said suture in one direction only. 90

9. In a fabric edging for female underwear, a suture formed by interlinking component thread scallops of the fabric to provide two separate strips whereby said aligning strips are adapted for hinge folding along the suture towards and away from each other. 95

10. A fabric edging for female underwear having two series of loops forming a suture, said loops being inter-linked so as to promote folding of the fabric along the suture in one direction only, and to form an ornamental edge when so folded consisting 100 of the two series of loops in interspatial relation. 105

In testimony whereof, I have hereunto signed my name at Philadelphia, Pennsylvania, this 16th day of December, 1920.

JAMES G. CURRIE.
